Stephen Darnold, of New Britain, Conn.

DES. 2079

ass to

Frank A. Corbin,

Letters Patent No. 2079 Dated June 6, 1866.

Design for a Coffin Handle.

The schedule referred to in these Letters Patent and making part of the same.

Shall whom it may concern:

Be it known that, Stephen Darnold, of New Britain, in the County of Hartford and State of Connecticut have invented and produced a novel and ornamental design for Coffin Handles and I do hereby declare that the following is a full, clear and exact description thereof, which will enable any one to make and execute the same, reference being had to the accompanying drawing forming part of these specifications.

The present invention relates to a certain new and useful design for handles to coffins, burial cases and caskets.

The drawing represents a front view of my design.

My design consists in a cross bar, with the outer end of each bar being of a spade-shaped shape, and their flat surfaces engraved with ornamental scrolls, &c. The cross bar is supported by a base, which with suitable screws is fastened to the burial case or casket in the position.

At each point of junction of the bar with base, the lower edge of the same, are short semi-circular grooved projections, grained above the surface of the cross, in sockets of which, ornamental engravings handle is inserted. This handle is made of a graceful shape, with its part b. cylindrical and grasped by the hand, highly ornamented by scrolls and curves terminating at each end with raised spiral grooved knobs, &c. The side parts a. & c. of the handle have spiral grooves along their surface, and across the opening of the handle is a neat scrolling bar, & an ornamental raised scroll, having an elliptical shape.

Patent as new and desired to secure by Letters Patent.

Frank A. Corbin.

85.2079

The herein described design for a handle to go
with, brief cases, caskets &c. the same consisting of the cross
and swinging handle having the ornaments and general config-
uration, represented in the drawing.
